UNITED STATES PATENT OFFICE

112,640

DESIGN FOR A TOOTHPICK CASE

Timothy L. Keough, Roxbury, Mass.

Application June 10, 1938, Serial No. 77,721

Term of patent 14 years

To all whom it may concern:

Be it known that I, Timothy L. Keough, a citizen of the United States, residing at Roxbury, in the county of Suffolk and State of Massachusetts, have invented a new, original, and ornamental Design for a Toothpick Case, of which the following is a specification, reference being had to the accompanying drawing, forming part thereof.

Figure 1 is a front elevational view of a toothpick case, showing my new design.

Figure 2 is an elevational view of the reverse side of Figure 1.

Figure 3 is a top plan view of Figure 1.

I claim:

The ornamental design for a toothpick case, as shown.

TIMOTHY L. KEOUGH.
